UNITED STATES PATENT OFFICE.

WILLIAM S. HADAWAY, JR., OF NEW ROCHELLE, NEW YORK.

SOCKET.

1,163,658.

Specification of Letters Patent. Patented Dec. 14, 1915.

Application filed May 8, 1914. Serial No. 837,106.

To all whom it may concern:
Be it known that I, WILLIAM S. HADAWAY, Jr., a citizen of the United States of America, and a resident of New Rochelle, Westchester county, and State of New York, United States of America, have invented certain new and useful Improvements in Sockets, of which the following is a specification, reference being had to the accompanying drawings, forming a part thereof.

My invention relates to electrical contacts and particularly to fixtures or sockets for supporting removable heating or lighting units.

One object of my invention is to provide a socket of the aforesaid character that shall be simple and inexpensive to construct and adapted to be secured to a sheet metal plate or base in close proximity to other similar fixtures.

Other objects and advantages of my invention will be set forth hereinafter, and in order that my invention may be thoroughly understood, I will now proceed to describe the same in the following specification, and then point out the novel features in appended claims.

Referring to the drawings: Figure 1 is a partially sectional elevation of a socket constructed in accordance with my invention and secured to a perforated supporting plate, arranged to receive additional sockets of the same character. A sectional elevation of the same parts is shown on a larger scale in Fig. 2. Fig. 3 is a top plan view and Fig. 4 a bottom plan view of the same socket.

The socket illustrated comprises a cup-shaped body 10 of sheet metal adapted to be secured to and supported by a base plate 15, a socket contact 20 and terminal members 25 and 30. The cup-shaped body 10 is provided with a central opening 11 in its base and an enlargement 12 near its open end having an extruded annular flange 13. The flange constitutes a bead flattened into an outwardly extending rib and the size of the enlargement beyond the rib is such that it extends freely through the hole 14 in the base plate 15.

The socket contact 20 is provided with helically corrugated side walls and is disposed within the body 21 of insulating material. The socket contact has a flange 22

at its inner end which is reinforced by a metal ring 23.

The terminal member 25 comprises a perforated arm 26 which is separated from the base of the body member by an insulating disk 28 and is secured in position adjacent to the base by means of rivets 27 which extend through suitable holes in the flange 22 and the ring 23 and electrically connect these members to the terminal 25. The terminal member 30 also has a perforated arm 31 which is separated from the arm 26 of the terminal 25 by an insulating washer 32 and is secured in position by a tubular rivet 33 of conducting material which extends completely through the base of the socket and is flanged over the terminal member 30 on the outside and over a metal washer 34, which is separated from the ring 23 by an insulating disk 35, on the inside. Thus, the parts are securely held in position while the terminal 25 is electrically connected with the contact cup while the terminal member 30 is connected to the tubular rivet 33 and the washer 34 which constitute an independent contact within the socket. The arrangement of the terminal members may be varied to accommodate the service condition under which the socket is to be used.

In mounting the socket on the base plate 15 the tubular enlargement 12 is thrust through one of the holes 14 in the plate, as shown in Fig. 1, then the edge of the enlargement is spun over as shown in Fig. 2 to form a substantial mechanical connection between the two parts. This mounting is particularly simple and reliable; it occupies a very small amount of space so that a plurality of sockets may be arranged close together and the distance between them will usually be determined solely by the size of the heating or lighting unit with which the socket is to coöperate.

In order to prevent the contact cup from turning in the cup-shaped base these members, when assembled, are correspondingly indented as shown at 36 in Fig. 2, and in order to prevent the base from turning in the plate each of the holes 14 is provided with a notch 37 into which an upturned lug 38 of the flange 13 is inserted.

The socket contact may be formed in any suitable manner and is not necessarily provided with corrugated or screw-threaded

walls. Other structural variations may be effected within the spirit and scope of my invention and I intend that only such limitations be imposed as are indicated in the 5 appended claims.

What I claim is:

1. A contact device comprising a metal base having a rib near one end and a portion beyond the rib adapted to extend 10 through a suitable hole in a supporting plate and be flanged over to secure the base thereto, electrically independent contact members, and a single means for securing the contact members together and to the metal base.
2. A contact device comprising a metal base having a rib near one end and a portion beyond the rib adapted to extend 15 through a suitable hole in a supporting plate and be flanged over to secure the base thereto, an electrical contact member secured within the base and insulated therefrom, and a terminal member on the outside of the base, insulated therefrom and electrically 20 connected with the contact member within.
3. A socket comprising a metal base having an annular rib near one end and a portion beyond the rib adapted to extend 25 through a hole in a supporting plate and be flanged over to secure the base thereto, a socket contact secured within the base and insulated therefrom, and a terminal member on the outside of the base insulated therefrom and electrically connected with 30 the contact member within.
4. A socket comprising a cup-shaped metal base having an annular rib near its edge and a portion beyond the rib adapted 35 to extend through a hole in a supporting plate and be flanged over to secure the base thereto, and a socket contact secured within the cup-shaped base and insulated therefrom, and a terminal member outside of said base and electrically connected with the 40 socket contact within.
5. A socket comprising a cup-shaped sheet metal base having an extruded annular rib near its edge and a cylindrical portion beyond the rib adapted to extend 45

through a circular hole in a supporting plate 50 and be flanged over to secure the base thereto, and a socket contact within the cup-shaped base and insulated therefrom, a pair of electrically independent terminal members outside of said base and insulated therefrom, and a single contact member constituting means for securing the parts of the 55 socket together.

6. A socket comprising a cup-shaped sheet metal base having an extruded annular rib near its edge and a cylindrical portion 60 beyond the rib adapted to extend through a circular hole in a supporter plate and be flanged over to secure the base thereto, a socket contact within the cup-shaped 65 base and insulated therefrom, a pair of electrically independent terminal members outside of said base and insulated therefrom, a single contact member constituting means for securing the parts of the socket together, 70 and means for preventing the rotative movement of the socket contact relative to the supporting plate.

7. A fixture comprising a cup-shaped metal base having a central hole in the bottom, a cup-shaped socket within the base and insulated therefrom, having an aperture 75 in the bottom opposite the opening in the base, a terminal having a perforated base secured to the bottom of the socket and insulated from the base, a second terminal, insulating washers located respectively in the bottom of the socket and over the base of the first named terminal, and a hollow central rivet for attaching the second terminal to 80 the socket and clamping the insulating washers in position to electrically separate the central rivet and the second terminal from the socket, said central rivet constituting an independent contact within the socket. 85

In witness whereof, I have hereunto set my hand this 6th day of May, 1914, in the presence of two subscribing witnesses.

WILLIAM S. HADAWAY, JR.
